SWING

William I. Smith, Perrysburg, Ohio, assignor to
The Hettrick Manufacturing Company, Toledo,
Ohio, a corporation of Ohio

Application November 20, 1943, Serial No. 511,082

1 Claim. (Cl. 155—61)

1

This invention relates to porch swings, but more particularly to porch swings having two seats facing each other supported for conjoint to and fro swinging movement, and an object is to produce a swing of this character in which the to and fro swinging movement is improved and in the nature of a relatively smooth and easy glide.

Other objects reside in details of construction, arrangement and operation hereinafter more fully described, and for purposes of illustration but not of limitation, an embodiment of the invention is shown on the accompanying drawings in which

Figure 1 is a side elevation of the swing;

Figure 2 is a fragmentary side elevation showing one side of the swing and indicating in broken lines the forward position of the swing; and

Figure 3 is an enlarged fragment of one end of the swing and showing particularly the link suspension, the section being taken along the line 3—3 of Fig. 1 with portion 10 and leg 11 removed for purposes of illustration.

The illustrated embodiment of the invention comprises a two seater swing with the seats facing each other and in which the supporting standard consists of tubing having a central floor engaging portion 10, from the ends of which rise legs 11. The upper ends of the legs 11 are joined to horizontal pieces 12. The rear ends of the horizontal portions are joined to downwardly extending portions 13. The low ends of the downwardly extending legs 13 connect to horizontally extending floor engaging portions 14 which connect at the opposite sides of the swing to similar legs 13. It will be understood that the supporting standard is the same for opposite sides of the swing.

From the above description it will be apparent that the supporting standard may be of a single length of tubing or if desired to facilitate shipment, portions of the standard may telescope to enable the structure to be disassembled for transportation purposes.

Suspended from the horizontal portions 12 are seat units A and B which are of similar construction. Each of these units comprises one or more seat and back units 15 which are secured to tubular side pieces 16 which are in the form of a U having vertically spaced horizontal portions 17 and 18 joined at the front by a vertical portion 19. An angle bar 20 connects the rear ends of the horizontal portions 16 and to this angle bar is secured the adjacent portions of the seat units 15. A sheet metal brace 21 connects respectively

2

to the horizontal portion 17 and vertical portion 19 and is suitably welded in place for strengthening purposes. A tubular rod 22 extends horizontally from one brace 21 to the other and is suitably bolted in position. An angle bar 23 connects the spaced vertical portions 19 and provides a support for the front end portion of the seat structure 15.

A pair of hangers 24 and 25 are pivoted to each 10 of the horizontal portions 12 of the supporting standard and incline downwardly to the horizontal frame portion 17 to which they are pivoted. It will be noted that the hangers 24 and 25 converge downwardly so that the pivotal connections 15 between the hangers and the frame portion 17 are closer together than the pivotal connections between the hangers and the horizontal portion 12 of the supporting standard. The arrangement of the hangers illustrated has been found empirically to afford a most satisfactory to and fro swinging movement free from objectionable jumpy motion.

It will be understood that the above description has been given in connection with one of the 25 gliders, but the structure of the other glider in facing relation is identical so that further description thereof is not necessary.

Connecting the two glider units is a platform 26 which is spaced below the horizontal portions 30 17 of the glider structures A and B. The platform comprises a series of horizontal braces 27 on which are connected a series of laterally disposed closely spaced slats 28. Fixed to the outermost braces 27 are metal hangers 29 which are 35 suitably secured as by screws at the lower ends to the end portions of the braces 27 and extend vertically upward and terminate in outwardly bent hooks to hook over the adjacent cross rod 22. The ends 29a of hooks 29 are indicated in 40 dotted lines in Fig. 3. It will be understood that there are four hangers 29, two being provided for the cross rod 22 of each of the units A and B. In this manner the two units A and B are connected and persons sitting on the units A and B 45 bracing their feet on the platform 26 can produce a free and easy, smooth gliding action. Figure 2 somewhat illustrates this movement which it will be observed, is free from substantial undulating action, this being to a large extent due to the hangers 24 and 25 and the manner in which they connect to the supporting standard and to the units A and B as above described.

From the above description, it will be manifest that I have produced an exceedingly simple and 50 relatively inexpensive swing which can, on a pro-

duction basis, be produced at a relatively low cost. The ease with which the swinging action can be started and the smooth and comfortable glide are important features of the structure.

It is to be understood that numerous changes in details of construction, arrangement and operation may be effected without departing from the spirit of the invention especially as defined in the appended claim.

What I claim is:

A swing comprising a pair of facing back and seat assemblies, each assembly having a horizontally disposed frame part arranged at each side and forming the lower end of the assembly, a vertically disposed frame part arranged at each side and forming the front of the assembly, a diagonal brace between each of the adjacent horizontally and vertically disposed frame parts, and a horizontal rod disposed crosswise at the front of the frame part and secured at its ends to said diagonal braces, a supporting standard including a horizontal member arranged above each frame part, legs extending downwardly from each end of said horizontal members, a central floor engaging member connecting the lower ends of adjacent legs, a floor engaging member connecting the lower end of the other leg and the corresponding leg on the other side of the standard,

5 pairs of spaced links pivoted at their upper ends to the horizontal members respectively and at their lower ends to the horizontal frame parts respectively, a platform between said back and seat assemblies and spaced downwardly from said horizontally disposed frame parts respectively, said platform including horizontal braces extending beneath the sides thereof, hangers fixed to and extending upwardly from the ends 10 of said braces, and downwardly facing hook members on said hangers loosely and pivotally engaging the adjacent horizontal rod.

15 WILLIAM I. SMITH.
